(57) **CLAIM**

The ornamental design for a precious stone jewelry, as shown and described.

DESCRIPTION

FIG. 1 is a perspective view of a precious stone jewelry in accordance with the present invention.

FIG. 2 is a right side view thereof, the left side view being symmetrical thereto.

FIG. 3 is a front view thereof, the rear view being symmetrical thereto.

FIG. 4 is a top view thereof; and,

FIG. 5 is a bottom view thereof.

The broken lines in the drawings illustrate environmental subject matter only and form no part of the claimed design.
